[57] ABSTRACT

An ingot base plug and, fixed on the top of the plug, a splash can.

3 Claims, 2 Drawing Figures

PATENTED DEC 3 1974

3,857,438

FIG.1

FIG.2

COMBINATION PLUG-SPLASH CAN AND METHOD OF USING SAME DURING CASTING

This invention relates to ingot moulds.

It is common practice, in the case of big-end-up ingot moulds to provide an aperture in the base of the mould through which a plunger may be forced to aid in ejecting the solidified ingot from the mould. In order that this aperture does not allow molten metal to escape during casting it is sealed prior to casting with a suitable refractory plug. Such plugs are described, for example, in U.S. Pat. No. 1,107,454.

Although it may be expected that erosion by impingement of the incoming molten metal stream would be confined to the refractory plug some erosion at the base of the mould does occur if other precautions are not taken.

Furthermore, it is well known that ingot quality may be reduced if there is a lot of splashing in the bottom of the mould as teeming of molten metal commences, and a very wide variety of proposals have been made to try and reduce such splashing in order to reduce its deleterious effects.

The most serious of these effects are the formation of cracks, the occurrence of inclusions and scabs; these may occur on the surface of the ingot or in its body depending on the character of the defect concerned. In some instances if the defect is very severe its occurrence in the rolled sheet or otherwise worked product may be found.

According to the present invention there is provided, in combination an assembly of an ingot base plug and, fixed on the top of the plug, a splash can.

This combination is highly advantageous. First, the splash can and plug are inserted in one operation only; second, the position of the splash can is fixed and it cannot be knocked sideways or overturned by the incoming stream of molten metal. Further, the splash can serves initially to restrict erosion by the molten metal stream to the top of the plug, thus avoiding erosion of the base of the mould and prolonging ingot mould life.

The shape and size of both plug and splash can may vary widely. Preferably the plug will be in the form of a solid refractory frusto-cone, and the splash can will be in the form of a hollow metal cylinder coaxial therewith. The ratio of cylinder height to diameter may vary from, for example, 1:10 to 1:1. The diameter of the splash can may be greater or less than that of the plug; most preferably it is slightly less. Other shapes for plugs may be required by unusual casting moulds. Other shapes for splash cans — e.g., a section of a square tube or triangular tube — are possible but are not preferred.

Preferably the assembly of plug and splash can is held together by a wire rod engaging the splash can at two opposite points and passing through a ring or wire loop

55

set in the upper face of the plug.

Preferably the wire rod is "kinked" at the point where it links with the loop. The wire rod preferably engages in opposite apertures in the splash can; the extreme ends of the wire rod may be bent over to prevent disengagement from the splash can.

This feature combined with the kink ensures that the splash can is held firmly in position when the first stream of molten metal impinges onto the base plug.

Alternatively, both ends of the wire rod may be threaded, and retaining wing-nuts or the like may be fitted thereon in order firmly to secure the rod and can.

In one particular embodiment the splash can may be formed of a strip of resilient metal — e.g., steel — with each of its ends turned back to form a tongue; such a strip is bent into circular form and the tongues interengage to prevent its springing back flat.

The invention is illustrated, by way of example, with reference to the accompanying drawings in which:

FIG. 1 is a perspective view from above of an assembly according to the invention, and

FIG. 2 is a side sectional view of the assembly of FIG. 1.

1. Referring to the drawing, the assembly consists of a bottom plug 1 bearing set in its upper face loop 2. A splash can 3, constituted by a sheet of mild steel formed to a circle by interengaging tongues 4, is held on to the plug 1 by a steel wire rod 5. Rod 5 engages holes 6 in the splash can 3. The rod 5 is "kinked" at 7 where it passes through loop 2. The ends of the rod 5 are bent over at 90° at 8.

I claim as my invention:

1. The combination for use in casting molten metal into ingot moulds having an apertured base plate comprising a plug for the aperture in the base plate, said plug being a solid frusto-cone of refractory material, a splash can, and means for fixing the splash can to the plug, said splash can being a hollow metal cylinder coaxial with the frusto-conical plug, the height: diameter ratio of the cylinder being 1:10 to 1:1, and the fixing means comprising a ring set in the upper face of the plug with a wire rod engaging the splash can at two opposite points and passing through the ring.

2. The combination of claim 1 wherein the splash can is formed of a strip of resilient metal with each of its ends turned back to form a tongue, and with the two tongues mutually interengaged.

3. In the casting of molten metal into an ingot mould having an apertured base plate, the steps of sealing, prior to teeming, the aperture in the base plate with the combination plug-splash can of claim 1 and then teeming molten metal into the mold.
